SPARK PLUG

Filed Oct. 10, 1929

UNITED STATES PATENT OFFICE

HECTOR RABEZZANA, OF FLINT, MICHIGAN, ASSIGNOR TO A C SPARK PLUG COMPANY,
OF FLINT MICHIGAN, A COMPANY OF MICHIGAN

SPARK PLUG

Application filed October 10, 1929. Serial No. 398,665.

This invention relates to spark plugs of the type commonly used in internal combustion engines. Such plugs are usually composed of a metal shell adapted to be threaded into the engine, and an insulating member of porcelain, mica or other suitable material, in which is carried an electrode member. These insulators are necessarily subjected to the very high temperatures developed in the combustion chamber, and in order to avoid the possibility of their becoming cracked or otherwise damaged from excessively high temperatures, it is essential that provision be made to carry away or dissipate as much of the heat as possible. In the usual type of plug, the heat is transferred from the insulator to the shell, and from the latter to the engine, by conduction. Due to the fact that the threaded connection between the shell and the engine interferes to a considerable extent with the rapid transfer of the heat, the insulator under certain conditions becomes excessively hot and as a result cracks, thereby rendering the spark plug inoperative. It is therefore an object of this invention to provide a spark plug construction in which the heat may be more readily and positively transferred to the combustion chamber wall, from which it may be carried away by the liquid in the cooling system. This is accomplished by eliminating the usual spark plug shell, thereby allowing the insulating member to come into direct contact with the wall of the combustion chamber. A tapered aperture is formed in the wall and the insulating member is correspondingly tapered so that it may be wedged into close contact with the wall in order to insure a more positive and rapid transfer of the heat by conduction. By rotating the insulating member in the tapered aperture at the time of assembly, with any suitable grinding compound placed between the two, the surfaces may be ground to exactly the same shape, similar to the manner in which valves are ground on their seats. Thus the maximum possible area of contact between the insulator and the combustion chamber wall is obtained, and the conduction of heat from the former to the latter is facilitated.

Another object of the invention is to construct a spark plug in which it is not necessary to provide the usual gaskets for preventing leakage of the gases from the cylinder. Such gaskets sometimes permit leakage of gas after the spark plug has been in use, due to the continual expansion and contraction of the shell relative to the insulating member. Due to the fact that the surfaces of the tapered aperture and the insulator in my improved spark plug are ground together to form a perfect seat, there is no possibility of leakage occurring between the two. By eliminating the gaskets and the usual metal shell, the cost of the plug is materially reduced.

Other objects and advantages will be apparent upon referring to the specification and accompanying drawings, in which:

Fig. 1 is a section through a portion of a combustion chamber wall, showing my improved spark plug assembled therein.

Fig. 2 is a section taken on the line 2—2 of Fig. 1.

Figs. 3—7 are views corresponding to Fig. 1, but showing modified forms of spark plugs.

The reference numeral 10 indicates a portion of an internal combustion engine which forms one wall of the combustion chamber. A cooling water jacket 12 is formed between the wall 10 and an outer wall 14. An aperture 16 is formed through both the walls for the purpose of permitting the insertion of a spark plug. This spark plug consists of an insulating member 18 formed of porcelain, mica or any other suitable material. A portion 20 of this member is tapered and fits into a correspondingly tapered portion 22 formed in a combustion chamber wall. The usual central electrode 24 is supported in the insulating member. The lower end 26 of this electrode is bent at a right angle to the main portion and extends quite close to a boss 28 formed on the inside of the combustion chamber wall 10. The distance between the end 26 of the electrode and the boss 28 is so set as to be exactly the same as the width of the spark gap in the ordinary type of spark plug.

At the time the insulating member 18 is

assembled in the aperture 16, it is preferably ground in place with any suitable grinding compound placed between the tapered portions 20 and 22. The insulating member 18 is rotated sufficiently to insure that the surfaces will be ground to exactly the same shapes so that the entire surface of the tapered portion 20 will be in contact with the tapered portion 22, thus insuring the maximum possible area of contact, which will permit a large amount of heat to be conducted into the combustion chamber wall from which it is removed by the circulation of the cooling water in the jacket 12.

Any suitable means may be provided for holding the insulator in place in the aperture 16. In Fig. 1 there is illustrated a quick detachable type of holding means, which consists of a gland nut 30 threaded into the wall 14, and/or which may be permanently secured therein in any suitable manner such as by welding. This gland nut has formed on it a plurality of projections 32 which engage cam surfaces 34 formed on the insulating member 18. Slots 36 are formed in the body portion of the insulating member to permit the latter to be inserted through the gland nut 30, the slots being of a slightly greater width than the projections 32. After this has been done, the insulating member is rotated and the cam surfaces 34 engage the projections 32 and serve to wedge the tapered portion 20 of the insulating member into firm contact with the tapered portion 22 of the aperture 16. Obviously this wedging action not only serves to bring about a better transfer of heat from the insulating member 18 to the combustion chamber wall, but also provides a tight seal between the two which prevents the escape of any of the explosive gases in the combustion chamber. The result is that no gaskets are needed as is the case in the usual type of spark plug.

In the form of plug shown in Fig. 3, a shoulder 38 is formed on the insulating member 40. The gland nut 42 in this construction bears against a sleeve 44 formed of copper or any other suitable material having a comparatively high coefficient of expansion. The opposite end of the sleeve 44 bears against the shoulder 38, and it will be readily seen that as the parts become heated and tend to expand, the sleeve 44 will expand more rapidly than the gland nut 42 and the combustion chamber wall, and will consequently serve to maintain a firm contact between the tapered portions of the insulator and the combustion chamber wall at all times, thereby preventing leakage of the explosive gases and bringing about a more uniform transfer of heat from the insulating member to the combustion chamber wall.

In the form shown in Fig. 4, the lower end of the central electrode 46 is not bent, but is spaced the desired distance above a ground

electrode member 48 secured in a boss 50 formed on the inside of the combustion chamber wall. A slightly different form of holding mechanism is shown in connection with this form. This consists of a fulcrum member 52 having an end 54 adapted to bear against the insulator member 56. The opposite end of the fulcrum member bears against the wall 14 or if desired against the insulator of another spark plug. A nut 58 threaded on a stud 60 serves to draw the fulcrum member against the insulator 56, thereby wedging the latter into firm contact with the tapered aperture in the combustion chamber wall. In this form a more rapid transfer of heat is provided for as well as a better seal, due to the increased area of the tapered surfaces.

In Fig. 5 is shown an insulating member 62 in which are supported two electrodes 64 and 66. This type of plug is more likely to be used in engines of the type wherein two spark plugs are provided for each cylinder, these plugs being connected in series with each other to insure that a spark will be produced in both plugs. In this type of installation the electrode 64 is connected to the distributor and the electrode 66 is connected to the other spark plug.

In the form shown in Fig. 6 a central electrode 68 is spaced the desired distance away from a second electrode 70 which is supported in the insulating member 72 in such a position that it contacts with the wall of the combustion chamber at 74. An advantage of this type of construction is that the width of the spark gap may be definitely determined before the plug is assembled in the aperture.

In Fig. 7 a slightly different form of plug is illustrated, wherein the insulating member 76 is composed of layers of mica, there being an axially extending insulating sleeve 78 of mica surrounding the central electrode 80. The lower portion 82 of the insulating member is tapered to fit into a tapered aperture 84, while a metal sleeve 86 surrounds the upper portion of the insulating member. Additional mica insulation 88 surrounds the electrode 80 and the axially extending insulation 78 above the sleeve 86. A gland nut 90 threaded into the wall 14 engages the sleeve 86 and serves to wedge the tapered portion 82 of the insulating member 76 into firm contact with the tapered aperture 84, to effect a tight seal and a rapid conduction of heat from the insulating member to the combustion chamber wall.

It will be understood of course that in all of the forms of plugs shown and described it is preferable to grind the tapered portions of the insulating members into place in the tapered apertures to insure as large an area of contact as possible, in order that there may be a more satisfactory transfer of heat and at the same time to provide a gas-tight seal. Obviously, any of the securing means shown

may be used with any of the types of spark plugs.

It is thought from the foregoing, taken in connection with the accompanying drawings, 5 that the construction and operation of the spark plug will be apparent to those skilled in the art, and that various changes in size, shape, and proportion may be made without departing from the spirit and scope of the 10 appended claims.

I claim:

1. In combination, a combustion chamber wall having therein a spark plug receiving opening, at least a portion of which is of 15 conical shape, an insulator body receivable within said opening and having a conical-shaped peripheral surface for engagement with the conical portion of the opening, an inwardly extending tongue at the opening, 20 and a cam surface on said body for engagement with said tongue to move the conical part into tight contact.

2. In combination, a combustion chamber wall having therein a spark plug receiving 25 opening, at least a portion of which is of conical shape, an insulator body receivable within said opening and having a conical-shaped peripheral surface for engagement with the conical portion of the opening, a series of 30 inwardly extending tongues at the opening, slidable through axially extending ways in the surface of said body, and a cam surface adjacent each way for engagement with the tongue upon rotation of the body to bring 35 the conical parts into tight contact.

In testimony whereof I affix my signature.
HECTOR RABEZZANA.
